(57) **CLAIM**

The ornamental design for a cutting tool, as shown and described.

DESCRIPTION

FIG. 1 is a perspective view of a cutting tool, according to a first embodiment;

FIG. 2 is a top plan view of the cutting tool shown in FIG. 1;

FIG. 3 is a side elevational view of the cutting tool shown in FIG. 1;

FIG. 4 is a side elevational view of the cutting tool rotated 180° relative to the side elevational view of FIG. 3;

FIG. 5 is a side elevational view of the cutting tool rotated 90° angle relative to the side elevational view of FIG. 4;

FIG. 6 is a side elevational view of the cutting tool rotated 180° relative to the side elevational view of FIG. 5;

FIG. 7 is a perspective view of a cutting tool, according to a second embodiment;

FIG. 8 is a top plan view of the cutting tool shown in FIG. 7;

FIG. 9 is a side elevational view of the cutting tool shown in FIG. 7;

FIG. 10 is a side elevational view of the cutting tool rotated 180° relative to the side elevational view of FIG. 9;

FIG. 11 is a side elevational view of the cutting tool rotated 90° angle relative to the side elevational view of FIG. 9; and,

FIG. 12 is a side elevational view of the cutting tool rotated 180° relative to the side elevational view of FIG. 11.

The broken lines in the drawings depict portions of the cutting tool which form no part of the claimed design.

The bottom view of the cutting tool does not form part of the claimed design.

(Continued)

The broken away symbols in the drawings indicate that any portion of the article beyond what is shown forms no part of the claimed design.
